J. H. ASTRUCK.

ASH TRAY.

APPLICATION FILED JAN. 11, 1916.

1,220,167.

Patented Mar. 27, 1917.

UNITED STATES PATENT OFFICE.

JOHN H. ASTRUCK, OF NEW YORK, N. Y.

ASH-TRAY.

1,220,167.

Specification of Letters Patent. Patented Mar. 27, 1917.

Application filed January 11, 1916. Serial No. 71,413.

To all whom it may concern:

Be it known that I, JOHN H. ASTRUCK, a citizen of the United States, and a resident of New York city, in the county and State of New York, have invented certain new and useful Improvements in Ash-Trays, of which the following is a specification.

This invention relates to an ash tray of novel construction and more particularly to novel and efficient means for supporting the cigars or cigarettes upon the rim of the tray.

In the accompanying drawing:

Figure 1 is a perspective view of an ash tray, embodying my invention;
Fig. 2, a plan;
Fig. 3, a section on line 3—3, Fig. 2;
Fig. 4, a section on line 4—4 Fig. 2;
Fig. 5, a section on line 5—5 Fig. 2, and
Fig. 6, a detail of part of the match box holding shoulder.

The body of the ash tray comprises a bowl preferably formed of vitreous or ceramic material and of circular or other configuration. It has a wall 1 of such thickness, as to form a horizontal rim 2 of such considerable width, as to constitute a rest for a cigar. Into this rim, are sunk, a plurality of grooves or rests 3 and 4, which serve for the accommodation of cigars or cigarettes. These grooves are so formed that they do not cross the wall radially or along a minimum length of path, but that they traverse the wall on a diagonal so that their length is somewhat greater than the thickness of the wall while furthermore the various grooves traverse the rim in different oblique directions. In this way, the length, and consequently the security of the rest is considerably increased, while furthermore, the inner ends of the cigars supported on the several rests, will be deflected from the center of the tray, so that they will not be liable to interfere with each other. As more fully shown in Fig. 5, the rest further-

more increases in depth from its outer toward its inner end, to impart a corresponding tilt to the cigar, and prevent the same from being readily knocked off.

In order to secure a match box to the tray, wall 1 is provided with a pair of opposed notches 5, that form between them, a projection or shoulder 6 which is integral with wall 1, and is sunk flush or below the rim thereof, so that it presents no unsightly 50 eminence and is not liable to be injured. Over shoulder 6 is adapted to be projected, a casing 7 which is designed to encompass a match box of conventional construction. Casing 7, is provided with a pair of resilient 60 end lugs 8 which are received by corresponding recesses 9, formed in the ends of shoulder 6. These lugs are furnished with bulges or protuberances 10, while recesses 9 have sockets 11 adapted to receive the same. 65 Thus by slipping the casing over shoulder 6, lugs 8 will spring into recesses 9, while protuberances 10 will be projected into sockets 11, thus securely holding the casing to the tray. When the match box is next 70 slipped into the casing, and over shoulder 6, its outer member will be projected over the lugs, so as to tighten the hold of the lugs on the shoulder, and to thus lock the casing to the tray.

I claim:

1. An ash tray comprising a bowl having a rim of a thickness sufficient to constitute a cigar rest, and a plurality of diagonally disposed grooves sunk into said rim 80 and traversing the same in different oblique directions.

2. An ash tray comprising a bowl having a horizontal rim of a thickness sufficient to constitute a cigar rest, and a groove sunk 85 into said rim and increasing in depth from its outer end toward its inner end, whereby a corresponding tilt is imparted to the cigar supported within said groove.

JOHN H. ASTRUCK.
